UNITED STATES PATENT OFFICE

ALBERT H. TINNERMAN, OF CLEVELAND, OHIO

DESIGN FOR A CASING FOR A VENTILATING UNIT

Application filed February 15, 1933. Serial No. 47,225. Term of patent 3½ years.

To all whom it may concern:

Be it known that I, ALBERT H. TINNERMAN, a citizen of the United States, residing at Cleveland, in the county of Cuyahoga and State of Ohio, have invented a new, original, and ornamental Design for a Casting for a Ventilating Unit, of which the following is a specification, reference being had to the accompanying drawing, forming a part thereof.

In the drawings, Fig. 1 is a side elevation of a casing embodying my design; Fig. 2 is a front elevation thereof; Fig. 3 is a top plan view thereof and Fig. 4 is a rear elevation thereof.

I claim:

The ornamental design for a casing for a ventilating unit, substantially as shown.

ALBERT H. TINNERMAN.
